(Cl. D67—4)

To all whom it may concern:

Be it known that we, Byron E. Freitag and Frederick Burggraf, Jr., citizens of the United States of America, residing at River Edge, New Jersey, and Livingston, New Jersey, respectively, have invented a new, original, and ornamental Design for a Water Cooler Top, of which the following is a specification, reference being had to the accompanying drawing, forming a part thereof, in which:

Fig. 1 is a top view of a water cooler top embodying our new design and;

Fig. 2 is a perspective view of the water cooler top of Fig. 1.

The portions in broken lines are for the purpose of illustration.

We claim:

The ornamental design for a water cooler top, as shown and described.
